[57] CLAIM

The ornamental design of a multi-fold casing, as shown and described.

DESCRIPTION

FIG. 1 is a perspective view of a multi-fold casing showing my new design;

FIG. 2 is a top view thereof;

FIG. 3 is a front side view thereof;

FIG. 4 is an end view thereof;

FIG. 5 is another end view thereof;

FIG. 6 is a rear side view thereof;

FIG. 7 is a bottom view thereof;

FIG. 8 is a perspective view showing the multi-fold casing in its partially opened condition;

FIG. 9 is a perspective view of showing the multi-fold casing in its fully opened position;

FIG. 10 is a top view of the multi-fold casing as shown in FIG. 9;

FIG. 11 is an end view of the multi-fold casing as shown in FIG. 9;

FIG. 12 is a front view of the multi-fold casing as shown in FIG. 9;

FIG. 13 rear view of the multi-fold casing as shown in FIG. 9; and,

FIG. 14 is a bottom view of the multi-fold casing as shown in FIG. 9.
